GARMENT FINISHING TABLE

James W. Steele, Kansas City, Mo.

Application October 26, 1931. Serial No. 571,085

6 Claims. (Cl. 68—10)

This invention relates to laundry appliances and it has particular reference to a garment finishing table.

The principal object of the invention resides in the provision of an ironing table, the operative area of which is purposely reduced below that of conventional ironing or finishing tables in order that it may be suited for the purposes for which the invention is primarily adapted. The invention is provided further with an auxiliary ironing table which is capable of movement relative to the main ironing table.

A further object of the invention is to provide a garment finishing table as a laundry appliance having such characteristics as to adapt the same to be used in connection with my shirt folding board, described in my co-pending application filed on January 30, 1931 and bearing Serial Number 512,356.

20 A further object of the invention resides in the provision of a finishing table of the character briefly mentioned in the foregoing in which suitable provisions are made for adjusting the auxiliary table relative to the operative area of the 25 main table. The auxiliary table has an operative area less than the area of the main table and is so connected to the main table that it may be disposed above the same and moved from side to side in the process of finishing a garment thereon, and 30 afterwards may be moved out of the way so that it will not interfere with any operations required to be carried out on the surface of the main table.

Still another object of the invention is to provide a convenient support for a hand iron, combined with other accessories, such as a sponge retainer and other receptacles necessary to the work of finishing a garment.

Broadly, the invention seeks to provide a garment finishing table, whose novel construction is such as to reduce to the very minimum the number of operations required of the operator in finishing the garment. In using the present invention, the operator may adjust the position of the garment on the table with one hand while the other may be used for ironing the garment and through the medium of the auxiliary table, the operator may finish a garment without having to release the iron at any time. This novel performance, which is due to the peculiar arrangement 50 of the elements constituting the complete assembly is instrumental not only in relieving the operator of considerable unnecessary work, but also enables the operator to increase his capacity and complete a greater number of garments in a 55 shorter period of time.

With the foregoing objects as paramount, the invention has particular reference to its salient features of construction and arrangement of parts, which will become manifest as the description proceeds, taken in connection with the accompanying drawing, wherein:

Figure 1 is a front elevational view of a finishing table constructed according to the present invention, and showing the auxiliary table in raised position, with broken lines representing it in lowered or operative position;

Figure 2 is a side elevation, showing the auxiliary table in lowered position, with broken lines representing it in raised or inoperative position;

Figure 3 is a perspective view, showing a garment partially finished thereon;

Figure 4 is a fragmentary detail view of the supporting frame for the auxiliary table; and

Figure 5 is a fragmentary detail view of the table and supporting frame inverted.

Continuing with a more detail description of the drawing, 1 designates a base or pedestal upon which is supported a rectangular table 2. The operating surface of this table is suitably padded and covered with a piece of durable fabric. The approximate size of the table may be determined by reference to Figure 3, showing its relationship in size to the garment 3 thereon.

While in some cases, the length of the table 2 may be of no importance, it is regarded in the present case as being more or less important in the finishing of shirts.

In this connection, it is pointed out that the shirt is first ironed or pressed by automatic pressing machines, especially in laundries having modern equipment. After the initial pressing operation, the sleeves of the shirt must be hand ironed, as well as the cuffs and around the shoulders and collar. It is for this hand-finishing operation that the invention is primarily adapted and it is preferred that the table 2 be of such length and width that the tail of the shirt as well as portions of the sleeves, hang over the edges in the manner shown in Figure 3. In being so disposed on the table, the shirt will assume a more natural position thereon and will lie flat. Moreover, the shoulder seams are more accessible to the operator and the fact that the sleeves overreach the edges of the table will enable the operator to tension the sleeves and move them relative to the body of the shirt so as to cause the latter to lie flat upon the board so that all creases and wrinkles may be effectively ironed out.

Affixed to and extending upwardly from the

back of the table 2 is a stationary hinge support 4, through which passes a shaft 5, disposed on a plane parallel with the surface of the table 2. Arms 6, which are integral with the frame 7 are 5 rotatably connected to the shaft 5 so that the frame 7 may be raised and lowered relative to the surface of the table 2. The frame 7, as apparent in Figures 1 and 2 supports the auxiliary table 8, which is likewise padded but is of 10 smaller dimensions than the table 2 so that when it is in operative position, as shown in Figures 2 and 3, the greater part of the garment 3 is exposed.

It has been stated that one of the objects of 15 the invention is to provide means by which the auxiliary table 8 may be moved relative to the table 2. This means consists in a series of right angle members 9, fixed to the underside of the table 8 and having their ends rigidly connected 20 with a pair of parallel rods 10, which are slidably received within suitable guide passages in the frame 7. It will be noted that each of the rods 10 is provided with a spaced, annular recess 11. These recesses are not of such depth as to 25 prohibit sliding movement of the table 8 relative to the frame 7 but only to hold or latch the same in either of two temporary operative positions, so that the table will not be accidentally displaced during the operation of finishing the 30 sleeves 12 of the shirt. Only a small amount of manual effort is required to release the table for sliding movement into either of these two positions.

Connected also to the frame 7 adjacent to its hinge support 4 is a pair of bracket members 13, shown only in Figure 2. When the frame 7 is lowered to bring the auxiliary table 8 into operative position relative to the table 2, the bracket members 13 engage said support 4 and thereby 40 serve to support the frame 7 and the table 8 carried thereby.

Disposed at one side of the main finishing table 2 is a rack 14, whose object is to support a hand iron so that it will be readily accessible to the operator standing in front of the table 2. The table 2 is also equipped with a receptacle 15 conveniently pivoted to the underside of the table 2. This receptacle is primarily intended to contain a sponge and is pivoted so that it may be moved 50 out of the way when not in use. Receptacles 16, situated at the rear of the table 2 are provided to contain accessories such as pins, collar supporting pasteboards and the like for the convenience of the operator.

55 In describing the operation of the invention the several steps in finishing a shirt will be set forth as an example and it is understood that the invention is not limited in any manner to the specific description to follow since it is obvious that the finishing table embodying the invention may be adapted to other uses not herein specifically set forth.

After the garment 3 has been initially ironed, as stated, it is placed upon the table 2 in the manner shown in Figure 3 so that the sleeves 12 will overhang the ends of the table and the tail portion of the shirt will overhang the front edge of the table. The operator then presses the shirt about the collar as well as about the shoulder 70 seams, it being pointed out that no part of the table 2 is out of reach while the operator is standing in the proper position before the table. This being the case, it is convenient for the operator to adjust the sleeves 12 of the shirt so that the shoulder seams will fall into the proper posi-

tion on the table and thus enable them to be pressed out effectively. Having completed the work of finishing the bosom, shoulders and those portions of the sleeves 12 nearest the body of the shirt, the operator, with the iron still in hand, grasps the auxiliary table 8 and brings the same into operative position over the table 2 and with the same movement adjusts the table 8 to one side of the table 2, as shown in Figure 3. Without returning the iron to the rack 14, the forepart of one sleeve is placed upon the table in the manner shown in Figure 3 and pressed out. The ironed sleeve is then replaced upon the board 2 and the operator, while still retaining hold of the iron with one hand, may now by a slight lift 90 and lateral push with his other hand, shift the board 8 to the opposite side of the table 2, as shown in dotted lines in Figure 3, after which, the forepart of the other sleeve of the shirt is placed upon the auxiliary board 8 and ironed in the same manner. After having completed this 95 operation, the sleeve is removed from the auxiliary board and the latter is returned to the inoperative position shown in full lines in Figure 1 and by the dotted lines in Figure 2, whereupon 100 the shirt may be removed from the table 2 and folded upon the shirt folding board described in my aforesaid application or in any conventional manner accepted or adopted by the laundries.

Manifestly, the construction shown is capable of considerable modification and such modification as is considered within the scope and meaning of the appended claims is also considered within the spirit and intent of the invention.

What is claimed is:

1. Apparatus for garment finishing operations, comprising a table providing a restricted ironing surface for the upper portion of the garment while leaving its nether portion depending from the front edge of said surface, and an auxiliary table member provided with an adjustable support at the rear of said first table permitting said auxiliary table to be positioned horizontally over said first table, said auxiliary table being also shiftable laterally in either direction for alternately supporting the garment sleeves in accessible position for the sleeve ironing operation by the operator at the front edge of the first table.

2. Apparatus for garment finishing operations, comprising a table providing a restricted ironing surface for the upper portion of the garment while leaving its nether portion depending from the front edge of said surface, an auxiliary sleeve-supporting table member, and means providing a pivotal support between said auxiliary table member and the rear portion of said first table whereby said auxiliary table may be swung into horizontal position over said first table, said auxiliary table being also shiftable laterally relative to its supporting means in opposite directions for alternately supporting the garment sleeves in accessible position for the sleeve-ironing operation by the operator at the front edge of the first table.

3. Apparatus for garment finishing operations, comprising a table providing a restricted ironing surface for the upper portion of the garment while leaving its nether portion depending from the front edge of said surface, and an auxiliary table member provided with means for adjustably supporting the same with reference to the rear edge of said first table and permitting said auxiliary table to be positioned horizontally over said first table and also shifted laterally in either direction for alternately accommodating the gar- 140

- ment sleeves in accessible position for the sleeve-ironing operation by the operator at the front edge of the first table, said supporting means including means for temporarily latching said auxiliary table in either sleeve-ironing position. 5
4. Apparatus for garment finishing operations, comprising a table providing a restricted ironing surface for the upper portion of the garment while leaving its nether portion depending from the front edge of said surface, an auxiliary sleeve-supporting table member, and a frame carrying said auxiliary table and provided with a pivotal support upon the rear end portion of said first table whereby said auxiliary table may be swung into horizontal position over the first table, said auxiliary table having limited sliding movement upon said frame in opposite lateral directions for alternately accommodating the garment sleeves in accessible position for the sleeve-ironing operation by the operator at the front edge of the first table. 10
5. Apparatus for garment finishing operations, comprising a table providing a restricted ironing surface for the upper portion of the garment while leaving its nether portion depending from the front edge of said surface, an auxiliary sleeve-supporting table member provided with a movable frame supporting said auxiliary table for swinging movement with reference to said first table whereby the auxiliary table may be moved into and out of horizontal position over the first table, said auxiliary table being slidably mounted upon said frame for limited shifting movement in either lateral direction for alternately accommodating the garment sleeves in accessible position for the sleeve-ironing operation by the operator at the front edge of the first table, and also having provision for latching said auxiliary table in either sleeve-ironing position. 15
6. Apparatus for garment finishing operations, comprising a table providing a main ironing surface for the upper portion of the garment while leaving its nether portion depending from the front edge of said surface, an auxiliary sleeve-supporting table member, and a frame carrying said auxiliary table and provided with a pivotal support upon the rear portion of said first table whereby said auxiliary table may be swung into horizontal position over the first table, said frame being provided with guide passages and said auxiliary table having guide rods slidably engaging said passages for permitting a limited sliding movement of said auxiliary table in either lateral direction for alternately accommodating the garment sleeves in sleeve-ironing position, one of said guide rods having spaced recesses for latching engagement with said frame for holding said auxiliary table in either sleeve-ironing position. 20
